APPARATUS FOR USE ON FLOATING
DRILLING PLATFORMS

Mercer H. Parks, Houston, Tex., assignor, by mesne assignments, to Esso Production Research Company, Houston, Tex., a corporation of Delaware
Filed Nov. 19, 1962, Ser. No. 238,397
5 Claims. (Cl. 254—172)

The present invention concerns apparatus for maintaining a substantially constant tension on drill pipe and the like suspended from a floating offshore structure.

When drilling wells into submerged lands from floating offshore drilling platforms, substantially constant weight must be maintained on the drill bit to keep it from being alternately pulled away from and dashed against the bottom of the borehole as wave action causes the floating platforms to vertically oscillate. Also, when running logging apparatus into or pulling it from a submerged borehole, a stable suspension point must be established so that oscillations of the floating platform will not prevent uniform travel of the logging equipment. A stable suspension point also is required to maintain completion equipment such as gun perforators at a desired level in the borehole when completing wells from floating offshore platforms.

It is a primary purpose of the present invention to provide apparatus to meet these needs.

One embodiment of the invention includes a cylinder and piston from which is suspended well drilling equipment and means including accumulators mounted on the cylinder for supplying constant pressure, variable volume hydraulic energy to the cylinder.

Another embodiment of the invention includes a piston and cylinder connected to a fixed point through resilient means; a reel for supporting a cable from which well equipment is suspended arranged on said resilient means connection; and means for supplying constant pressure, variable volume hydraulic energy to the cylinder.

The above object and other objects and advantages of the invention will be apparent from a more detailed description thereof when taken with the drawings wherein:

FIG. 1 is a vertical view of a drilling platform floating on a body of water with the apparatus of the invention for controlling bit weight mounted on the platform and connected to the drilling equipment;

FIG. 2 is a vertical view of a portion of the apparatus shown in FIG. 1;

FIG. 3 is a view taken on line 3—3 of FIG. 2;

FIG. 4 is a view taken on line 4—4 of FIG. 2;

FIG. 5 is a diagrammatic view of another portion of the apparatus shown in FIG. 1;

FIG. 6 is a vertical view of one form of apparatus of the invention for use in conjunction with logging apparatus; and

FIG. 7 is a view similar to that shown in FIG. 6 but illustrating a different embodiment.

Referring to the drawings in greater detail, in FIG. 1 is shown an offshore drilling platform or barge 10 anchored and floating in a body of water 11, and on which is arranged conventional drilling equipment, including derrick structure 12, live line 13, dead line 14, crown block 15, traveling block 16, circulating fluid conduit 18, swivel 19, rotary 20, and draw works 21. A borehole 25 is being drilled in the area underlying the body of water 11 by means of a drill bit 26 carried on the end of a string of drill pipe 27, the upper end of which is connected to a Kelly joint 28, which in turn is connected to the swivel 19. A part of the apparatus for maintaining substantially constant weight on drill bit 26 to compensate for vertical movement of platform 10 generally designated 30a is in-

2

terposed between block 16 and swivel 19. The remainder of the compensating apparatus generally designated 30b is positioned on the drilling platform.

Details of apparatus 30a and 30b are shown in FIGS. 2—5. Part 30a of this apparatus includes an elongated cylinder 35 suspended from traveling block 16 by links 36. Cylinder 35 is provided with an opening 37 in its upper end and an opening 38 in its lower end. The latter opening has connected to it a conduit 39. A piston 40, which divides the interior of cylinder 35 into upper and lower chambers 41 and 42 respectively, is slidably arranged in cylinder 35. A rod 43, from which drill pipe string 27 and drill bit 26 are suspended through swivel 19, extends through the lower end of cylinder 35 and is attached to piston 40. A seal 44, arranged in the lower end of cylinder 35, closes off the space surrounding rod 43 in the opening in cylinder 35 through which rod 43 extends in order to prevent leakage of liquids from chamber 42. Three accumulators 45 are secured to cylinder 35 by means of upper and lower brackets 46. Each accumulator is provided with a floating or free piston 47 which divides the interior of each accumulator into upper gas-containing and lower liquid, e.g., oil or water-containing chambers 48 and 49 respectively. High pressure gas is supplied to chamber 48 through nipple 50, a manifold 51 and a conduit 52. Valves 53 and 54 and a pressure regulator 55 are in conduit 52 which connects to a static source of fluid pressure 56 (see FIG. 5) as for example, nitrogen bottles. Lower chambers 49 fluidly communicate with a reservoir of liquid 60 through a connecting manifold 61 and a conduit 62. Conduit 39 also connects into manifold 61. A conventional, commercially available, diaphragm-operated motor valve 63, such as disclosed on page 1864, "Composite Catalog of Oil Field Equipment and Services," 1962—63, is arranged in conduit 62 and controls flow of liquid therethrough. Valve 63 is in turn controlled by liquid pressure in conduit 39, through a connecting conduit 64. A manually operable valve 65 is positioned in conduit 39. The remainder of apparatus 30b, as seen in FIG. 5, includes a pump 66 which when driven by a motor 67 draws liquid from reservoir 60 through a conduit 68 and feeds it to conduit 39.

The pressure of the oil in chamber 42 determines the force or weight on drill bit 26. The higher the pressure in chamber 42, the less will be the weight on the drill bit; and accordingly, the lesser the pressure in chamber 42, the greater will be the weight on the drill bit. Therefore, by controlling the liquid pressure in chamber 42, the net weight of the string of drill pipe 27 placed on drill bit 26 can be regulated, and to maintain the net weight on drill bit 26 substantially constant, the pressure of the oil in chamber 42 must be maintained substantially constant.

In order to maintain the liquid pressure in chamber 42 constant, pressure fluctuation in chamber 42, caused by vertical movement of cylinder 35, resulting from vertical movement of platform 10, must be compensated for by the pressure system described supra. Accumulators 45 provide a rapid response to pressure transients caused by the vertical motion of drilling platform 10, whereas reservoir 60 and its associated equipment, pump 66 and motor valve 63, provide for system volume changes associated with increased depth of borehole 25 as drilling progresses, and large movements of drilling platform 10.

The apparatus of FIGS. 1—5 operates in the following manner. When wave action causes drilling platform 10 to rise cylinder 35 also is carried upwardly relative to piston 40; and downward movement of platform 10 causes cylinder 35 to move downwardly relative to piston 40. When cylinder 35 rises relative to piston 40, pressure of the oil in chamber 42 increases. To maintain

piston 40 at a relatively constant level, liquid in chamber 42 discharges through conduit 39 and manifold 61 into chambers 49 of accumulators 45 where the increased pressure acts against floating pistons 47 to move them upwardly and increase in turn the pressure of the gas in chambers 48. Excess pressure in chambers 48 may be released through a pop-off valve 51a arranged in manifold 51. On the other hand, when cylinder 35 moves downwardly in response to downward movement of platform 10, in order to maintain piston 40 at a constant level, liquid must be supplied to chamber 42 to compensate for the decreased pressure caused by the increased volume of chamber 42. This liquid is supplied by that in chambers 49 and is forced through conduit 39 via a manifold 61 into chamber 42 by gas pressure in chambers 48 supplied thereto from the gas storage 56.

Pump 66 is operated continuously to force liquid from reservoir 60 into chamber 42 through conduit 39. Once the pressure in chamber 42 has been equalized by the liquid supplied from chambers 49 of accumulators 45, additional liquid from reservoir 60 is supplied to chambers 49, as required to effect full compensation for movement of platform 10. Also, when excess liquid from chamber 42 attempts to feed into chambers 49, as 40 moves downward, it is discharged into reservoir 60 through valve 63 by the pressure controlled conduit 64, which senses the increased liquid pressure in conduit 39. The excess liquid pressure then is discharged into reservoir 60. In general, small movements of cylinder 35 resulting from slight wave action will be compensated for by liquid transmitted from and into accumulators 45, whereas large movements of cylinder 35 will be offset by pump 66 and reservoir 60, as well as accumulators 45 and static source 56.

The pressures in the system must be increased to compensate for the additional weight of the drill string when lengths of drill pipe are added as the borehole is drilled deeper and deeper, or increased or decreased when it is desired to increase or decrease respectively, the weight it is desired to maintain on the drill bit. Dimensions and working pressures are dependent upon the various physical factors which will be well known for specific applications and upon engineering judgment in such matters as materials and safety factors.

The sensitivity of control of the position of piston 40 depends on the compressibility and volume of gas contained in accumulators 45. As mentioned supra, to maintain sensitivity of accumulators 45 as the operating pressure level increases, it is necessary to add gas to chambers 48 as the depth of the drill hole increases, and to supply gas to chambers 48, an air receiver continuously charged by an air compressor may be employed instead of the gas bottles 56 shown.

Accumulators 45 are mounted adjacent control cylinder 35 in order to eliminate any time lag in response to movement of cylinder 35. As an example, assume drilling platform 10 is floating in 15 foot waves, with a possibility of having a vertical velocity of 10 to 20 feet per second. To compensate the piston for this movement of cylinder 35, the controls must respond rapidly enough to prevent appreciable movement of the position of swivel 19. When the hydraulic fluid is transmitted through a great length of piping, the time for the pressure impulses to travel through this liquid may permit movement of the swivel some distance which, of course, is not desired. Therefore, in order to make the apparatus more sensitive, the accumulators are mounted adjacent the control cylinder.

Arrangements of apparatus for running logging and completion tools from floating offshore structures in submerged wells are shown in FIGS. 6 and 7. The compensating apparatus is similar to that described for the apparatus used to maintain constant weight on drill bit; however, it is dimensionally smaller since it is to be used to support equipment much lighter than the drill string 75

and drill bit. Thus, a traveling block 16 connects to a cylinder 35' through links 36', and accumulator cylinders 45' are mounted on cylinder 35'. The upper ends of cylinder 45' fluidly communicate with a source of fluid pressure through conduit 50' and 51' and manifold 52'. A rod 70, which connects to the piston in cylinder 35', is coupled to a turnbuckle 71 by a tension spring 72. The lower end of turnbuckle 71 is secured to the wellhead 73 at a fixed point 74, which may be either below water surface as shown, or above it. A sheave 75 is clamped as at 76 to rod 70. A logging cable 77 feeds from a spool or reel 78 mounted on drilling platform 10 through a pulley 79 also mounted on drilling platform 10 and over reel 75.

In the FIG. 6 embodiment the apparatus for supplying fluid pressure to the underside of the piston in cylinder 35' to maintain a constant weight on the logging tool, or to maintain the completion tool in a steady position in the borehole, is the same as that described for the drilling apparatus of FIGS. 1-5.

However, in FIG. 7 a somewhat different arrangement is shown in which the motor valve is controlled by a solenoid rather than fluid pressure. Thus, valve 80 is controlled through line 81 by a Wheatstone bridge 82 mounted on one of the accumulators 45'. In turn, the Wheatstone bridge 82 is controlled by a line 83 connected to a strain gauge 84, mounted on rod 70 below reel 75.

The operation of this equipment is as follows: In the apparatus of FIG. 6 movement of drilling platform 10 upwardly or downwardly increases or decreases the tension in rod 70, which has been preset by adjusting turnbuckle 71 and spring 72. The change in tension in rod 70 produces a change in the pressure in cylinder 35' below the piston, which is reflected through the conduit to open pressure operated valve 63' to restore the liquid pressure initially existing and through it the tension initially existing in rod 70, and the vertical position of reel 75. The operation of the apparatus of FIG. 7 is similar, except that in this instance a strain gauge 84 transmits increases or decreases in the tension in rod 70 to Wheatstone bridge 82, which is balanced at a selected pressure. In this manner the increase or decrease in tension is transmitted to the solenoid valve 80 by the Wheatstone bridge 82, to release more or less liquid from accumulators 45' and cylinder 35'. Thus, by release or increase of tension in rod 70, strain gauge 84 unbalances Wheatstone bridge 82 in one direction or the other, and the unbalance is transmitted to solenoid valve 80, which adjusts its opening to control flow of fluid from cylinder 35'. As in the case of the apparatus for maintaining bit weight, dimensions and working pressures will depend upon known physical factors and engineering judgment for each application.

Having fully described the nature, objects, and elements of my invention, I claim:

1. Apparatus for suspending a tool in a borehole on a cable from a floating offshore drilling platform comprising:

means mounted on said platform attached to said cable for raising and lowering it;

suspension means mounted on said platform including a cylinder having a piston slidably arranged therein; liquid in said cylinder below said piston;

tension means having an adjustable tension preset to a selected tension securing said piston to a fixed, immovable point;

a sheave attached to said tension means over which said cable is fed; and

means responsive to changes in tension in said tension means resulting from vertical movement of said platform adapted to compensate for motion of the tool arising from displacement of the platform and suspension means.

2. Apparatus as recited in claim 1 in which said tension means includes means for releasing more or less liquid

from said cylinder in response to increases or decreases in tension in said tension means.

3. Apparatus as recited in claim 2 in which said tension means comprises a rod, a spring and a turnbuckle connected together.

4. Apparatus as recited in claim 3 in which said means responsive to changes in tension in said tension means comprises a strain gauge attached to said rod; a Wheatstone bridge controlled by said strain gauge; and a solenoid valve controlled by said Wheatstone bridge.

5. Apparatus as recited in claim 4 including at least one accumulator mounted on said cylinder having a movable pressure responsive member dividing said accumulator into first and second chambers; means for supplying gas under pressure to said accumulator first chamber, said accumulator second chamber containing liquid in fluid com-

munication with said cylinder; a liquid reservoir; and a pump for supplying said cylinder with liquid, said reservoir liquid being in fluid communication via said pump with said accumulator second chamber.
